UNITED STATES PATENT OFFICE.

HENRI JULIEN, OF OTTAWA, CANADA.

IMPROVEMENT IN ADDRESS-PRINTING MACHINES.

Specification forming part of Letters Patent No. 80,285, dated July 28, 1868.

To all whom it may concern:

Be it known that I, HENRI JULIEN, of Ottawa, Canada, have invented a new and useful Improvement in Addressing-Presses; and I do hereby declare that the following is a full, clear, and exact description thereof, which will enable others skilled in the art to make and use the same, reference being had to the accompanying drawings, forming part of this specification.

The nature of my invention relates to improvements in addressing-presses to be used in newspaper and other such establishments where it is required, at frequently-recurring periods, to address great numbers of papers or documents to the same lists of names and places, whereby the same may be done by an automatically-operating machine with only the attendance of one person; and it consists in the arrangement of a vertically-reciprocating press, under which the form or galley containing the names and places of residence, set up in type, is caused to pass with an intermittent motion, on which the folded papers lie, to be forced down by the said reciprocating press to receive the impression of the type, and in the different combinations and arrangements of mechanism embodied in the said automatic machine to effect these operations, as will be more fully described on reference to the accompanying drawings, in which—

Figure 1 is a longitudinal vertical sectional view on the line *x x* of Fig. 3, looking in the direction of arrow *a*. Fig. 2 is a section on the same line, looking in the direction of arrow *b*. Fig. 3 is a transverse section on the line *y y* of Fig. 1.

Similar letters of reference indicate corresponding parts in all the figures.

A represents the vertically - reciprocating press, which receives its motion from the driving-shaft *K* through the medium of pinion *I*, wheel *F*, connecting-rod *E*, oscillating shaft *D*, segmental wheel *C*, and rack *B* on the said reciprocating press *A*.

L is a sliding table, which carries the forms or galleys and slides in a dovetailed groove in the top *N* of the frame-work of the machine, and which receives intermittent motion through the medium of the ratchet-bar *O*, affixed to brackets projecting downward from the said slide, pawl *P*, oscillating arm *Q*, connecting-rod *R*, and eccentric *S* on the shaft *H*.

T is an oscillating cam-shaft, connected to the hand-lever by means of the cranks *a a'* and connecting-rod *e*.

f and *f'* represent cams on the shaft *T*, which are designed to throw the mechanism for operating the press and the sliding carriage out of or into gear with the driving mechanism.

g is a lever, pivoted at *h*, one end of which is in a position to be acted upon by the cam *f* on the oscillating shaft *T*. The other end has a vertical slotted projection and carries the end of the connecting-rod *E*. The cam *f'* projecting from the oscillating shaft *T* is in a position to raise the pawl *P* out of connection with the rack *O* when turned in the proper direction.

l is a foot-treadle connected to the crank *n* by rod *m*, and may be used to operate the machine by foot-power.

p is a spiral spring wound around the shaft *D*, one end being fastened to the same and the other to a bracket, *r*, projecting from the framework of the machine. The said spring bears the shaft *D* in a direction to raise the press *A* up from the galley when it is thrown out of gear with the driving-power, and also assists the gears *C* and *B* in raising the same while at work.

A' is a chute or slide, on which the folded papers may be fed to the galley on which they are carried, and under the press.

B' are troughs resting on brackets *C*, fixed to the framing under the operating parts of the machine, for holding the galleys or stereotype-plates.

When the machine is set in motion by power applied to the driving-shaft, the cam-shaft *T* being moved by the hand-lever *O* so that the cams on the same will admit the pawl *P* to fall into connection with the rack *O* and the connecting-rod *E* into connection with the wrist-pin on the crank of shaft *D*, motion will be communicated to the press and to the slide carrying the stereotype-plates or galleys, when, the folded papers being fed over the chute *A'* onto the said plate, they will rest on the type as they are carried under the press, and, being pressed hard onto the said type, will receive the impression of the same on their undersides. As one plate passes over the table it may be taken off and put in its appropriate trough on the brackets *c'*. Then by turning the hand-lever *U* in the proper direction the pawl *P* will

be thrown up out of connection with the rack O and the connecting-rod E thrown out of connection with the crank on the shaft D, whereby the motion of the press and sliding table will be suspended, when the table may be moved back to the place of beginning for the reception of another plate or galley.

Having thus fully described my improvements, what I claim, and desire to secure by Letters Patent, is—

1. The combination, with the vertically-sliding press A, of the rack B, pinion C, shaft D, spring p, and the mechanism for operating the

shaft D, substantially as and for the purpose described.

2. The combination, with the pawl P and connecting-rod E, of the mechanism for connecting them and disconnecting them with the parts to which they communicate motion, substantially as and for the purpose described.

The above specification of my invention signed me this 5th day of February, 1868.

HENRI JULIEN.
